J. Granville Hayes
ATTORNEY

UNITED STATES PATENT OFFICE.

HARRY BRIDGMAN SMITH, OF NEW YORK, N. Y., ASSIGNOR TO BRIDGMAN & RUBIN, INC., OF NEW YORK, N. Y., A CORPORATION OF NEW YORK.

BOX-COVER-MARGIN TURN-IN MECHANISM AND METHOD.

Application filed October 26, 1925. Serial No. 65,028.

The invention relates to improved mechanism and methods for turning in and affixing projecting cover margins of boxes to inner shell-surface margins to provide the desired 5 attractive "finish" at the open edges of the box part.

It has hitherto been the practice to place a box part—body or cover section of a paper box—having a continuous cover margin 10 projecting beyond the open edges of the side walls in the planes of the walls, upon a movable form, to turn the cover margins inward horizontally by laterally moving blades or "tuck-in fingers," and then to apply another 15 form or plunger substantially fitting the inner contour of the box, to turn the margins in and down adjacent the inner faces of the shell-walls, and then to apply pressure laterally against the last mentioned 20 form to press the cover margins in position. Since the projecting margin is continuous, that is without division of the margin paper at the corners of the box, these operations involve the formation of overlapping portions or "tuck folds" at the corners, which 25 are often more or less irregular, bulky and unsightly in appearance.

The general purpose of the present invention is to provide a method of turning and 30 affixing cover margins which eliminates the necessity for the use of any box-part supporting form or plunger, or any laterally moving members to turn the margins horizontally, and any form or plunger to turn 35 the horizontal margins down adjacent the walls, and instead provides for placing the box part on any simple support, such as a vertically movable table, moving the box part itself laterally to co-operate with one 40 or more members which turn one or more adjacent cover margins to horizontal position, and for then moving the box part vertically to turn down the horizontal margins by 45 co-operation with relatively stationary turning members, after which pressure is applied to affix the margins. The method is also especially devised, as more fully explained hereafter, to co-operate with a box part having the projecting cover margins separated 50 or slit at the corners so that no tuck-fold will be produced and the margins will be folded and pressed down smoothly at the corners without increased thickness or other

undesirable features. The method may be performed with various mechanisms, but the 55 invention also includes mechanism or a machine, sufficiently represented by one example shown in the drawings, for carrying out the method, which is of simple organization and therefore may be produced at moderate 60 cost and which enables a large output to be produced economically because of the simple character of the machine operations.

The characteristics and advantages of the invention are further sufficiently explained 65 in connection with the following detail description of the accompanying drawing, which shows one representative embodiment of the invention. After considering this example, skilled persons will understand 70 that many variations may be made, and I contemplate the employment of any structures that are properly within the scope of the appended claims.

Fig. 1 is a vertical section at 1—1, Fig. 2, 75 of mechanism embodying the invention in one form.

Fig. 2 is a view, mainly in top plan, with some parts broken away and some in section.

Fig. 3 is a sectional detail. 80

Fig. 4 is a perspective view of one corner portion of a box part having projecting cover margins ready for the operation of the present machine, or the performance of the invention-method. 85

Fig. 5 is a similar view showing a completed box part.

The machine is built upon or around a frame which includes a base 1, uprights 2, and a generally L-shaped top piece 3 which 90 connects the upper ends of the uprights. A vertically movable support or table 4 is carried by a vertical bar 5 located in guides 6.

The top plate 3 comprises members arranged at a right angle, and each of these 95 supports similar turning and pressing mechanism capable of operating simultaneously on the projecting cover margins of two adjacent box walls. Each of these mechanisms includes a base 10 channeled to fit a longitudinal guide rail 11 on the corresponding frame member 3 so that the turning and pressing unit may be adjusted and secured in position by screws 12. A bracket 13 carried by base 10 supports a stationary turning and pressing bar 14, which may be de-

tachably secured by clamps 15. The outer, lower edge or corner 16 of the bar is beveled or rounded as shown. The adjacent ends of the two bars 14 are mitered so that they fit 5 closely together, with a sharp and square vertical outer corner.

A horizontally reciprocable presser bar or strip 20 to co-operate with each bar 14 is supported by rods 21 which pass through bearing holes in brackets 13 and base lugs 22. Helical springs 23 about the rods acting between brackets 13 and stop collars 24 on the rods, serve to normally retract the movable presser bar. The bar has a central stem or 10 rod 25 passing through bearing holes in bracket 13 and a base lug 26. The movable presser bar usually has an outer facing 28 of rubber or other suitable compressible material.

20 The movable pressers may be operated in various ways, for instance, by mechanical linkage; but for the sake of simplicity and manufacturing economy, hydraulic operating means are desirably employed. For each 25 presser bar a hydraulic casing 30 is mounted by means of brackets 31 on one of the bases 10. This casing encloses a diaphragm 32 which acts on the head 33 of a stem 34 passing through a bearing hole in the casing 30 and having its outward end opposed to the end of stem 25 above mentioned. The hydraulic chambers of the two casings are connected by pipes 40 to a union 41, and this union is connected to the chamber of a similar 35 hydraulic casing 42 mounted on base 1 and having similar diaphragm and stem arrangements. Stem 34 of the actuating hydraulic appliance 42 is opposed to a short stem 45 mounted in a bearing hole 46 in the base. A 40 suitable quantity of a liquid, such as oil, is provided, to substantially fill the hydraulic system.

Formed on or connected to the lower end 45 of table supporting bar 5 is a screw 50 engaging the threaded bore of a collar 51 having an annular channel 52 and provided with a hand wheel 53 for vertical adjustment. A lever 54 fulcrumed on a frame upright 2 at 55 has a yoke provided with studs 56 engaging in channel 52. The lever also has a cam roller 58 engaging a cam 59 carried by an arm 60 secured to a rock shaft 61 mounted in bearings in frame brackets 63. Also secured on the rock shaft is a pedal lever 65 55 having a treadle 66 convenient to the operator. The hub of lever 65 is formed with a cam 68 co-operating with the outward end of stem 45. An adjustable stop screw 70 in the frame brackets 71 co-operates with arm 60 to limit upward or return movement of lever 65, which may be urged in that direction by suitable means, such as a spring 75.

Fig. 4 shows two adjacent side walls y and z of a box part B. Covering material, usually 65 paper, has been applied to the outer faces

of these walls with margins m and n of this paper projecting above the edges of the shell walls at the open side of the box part. These margins, such as m and n , may be connected or continuous at the box corner, but preferably, for the purposes of the present invention, these margins are separated by a corner slit s , by methods and mechanism of my invention not here shown or described, or in other ways. The inner faces of the margins are coated with adhesive as indicated by stippling, this having usually been applied to the cover paper before its application to the shell.

One of the box parts B is placed on table 4, the height of which has been adjusted by manipulation of the hand wheel 53 to suit the height of side walls, such as y , z . When the box part is placed on the table the latter is in retracted or lower position, and the movable presser bars 20 are retracted, as shown in Fig. 1. The operator slides the box part horizontally on the table toward one or both of the movable presser bars 20. When two of these bars, angularly arranged as shown, are employed, the sliding action will be diagonal or at an angle of 45°, so that the walls y and z abut against the two presser bars 20 substantially simultaneously, and the box corner is then located as shown in Fig. 2, at the slightly-spaced corner provided by the adjacent ends of bars 20. If only one pressing mechanism is employed, as may be done in some cases, (the other pressing mechanism then being removed or inactive, or the machine being redesigned accordingly) the movement of the box part is at a right angle to the presser bar 20 employed. In either case, the described movement of the box part brings the upward projecting cover margins m or n , or either of them, in contact with the outer face of the fixed turning and pressing bar or bars 14, which turn these margins to horizontal position, as clearly shown in Fig. 1. When only one turning bar 14 is used, the turning action will be a straight or right-angle movement with relation to the margin, such as n and the bar 14, but if two are employed the action will be diagonal or angular, but because of the free sliding engagement of the cover margins against the turning bars, the margins in either case are turned smoothly to horizontal position.

The operator now steps on treadle 66, depressing the lever 65, and cam 59 acting upon its roller lever 54 elevates bar 5 and the table, moving the box part upward so that the upper portions of the shell walls pass upward between the pressing bars 14 and 20 of each cooperating pair. In this movement the lower faces of bars 14 engage the horizontally turned cover margins of the shell m and n , and turn them down adjacent inner-surface margins of the shell walls x y and z .

The rounded inner corners 16 of bar 14 provide for a smooth turning action without bumping against the upper edges of the shells or injury to the cover paper. The depression of the treadle 66 is continuous, and in its further movement cam 68 engages the end of stem 45, which is moved rearward (to the left in Fig. 1) and acts on stem 34 to move its head 33 and so to actuate the dia-
phragm 32 and force the liquid in the hydraulic chamber through pipes 40 to the upper hydraulic chambers 30, and so in an obvious way the movable presser bars 20 are moved outward and squeeze the upper portions of the box walls against bars 14, and press the inturned cover margins firmly in position so that they adhere to the inner shell surfaces by means of the previously applied adhesive. Because of the previous separation of the margins by the slits or otherwise, the horizontal turning and the vertical or inturning actions are smoothly and easily performed at the corners, as well as along the main stretches of the margins, without necessity for the formation of any corner tuck folds, and the adjacent ends of the margins smoothly abut, as shown in the finished box part in Fig. 5, or else they may slightly overlap without, however, any appreciable or noticeable thickening or bunching of the cover material at the corner. The inner corner formation is very smoothly and firmly pressed by the closely meeting ends of the inner pressing bars 14, as clearly shown in Fig. 2.

The operator then releases treadle 66; the lever rises automatically by spring action, first causing retraction of the movable presser bars 20 by action of their springs, and then cam 59 is retracted and the table drops by gravity, bringing the box part down to the position of Fig. 1, and it is then removed by the operator. When two adjacent margins have been simultaneously turned and pressed, the box part is turned half way round and the operations described are repeated to complete the box. If, however, only one margin is pressed at a time, as when a single pressing unit is employed, the box part is turned one-quarter of the way around after each operation, and the operations are repeated until the box part is finished.

If only a single pressing unit is used, the cooperating presser bars 14 and 20 may be made long enough to turn and press the margin on the longest or side wall of the box, and a notch may be provided in the lower portion of the fixed bar 14, as at 14^a, wide enough to accommodate the thickness of the shell wall and cover paper, with moderate clearance, this notch being spaced from one end of the bar a distance equal to the length of the shoulder or end wall of the box. The short or end wall margins may then be pressed by positioning the box ends against bar 20, and

when the box is raised for the vertical turn-
in the side wall will pass up into the notch 14^a.

The turning and pressing bars 14 may be provided in different lengths for different box dimensions, and may be readily removed and replaced. The outer pressing bars 20 may also be dimensioned for different boxes, but may usually be of such lengths and the table 4 may also be of such dimensions, that the stated parts will accommodate boxes of varying dimensions, within any reasonable range.

The method will be understood in detail from the preceding explanation of its performance in connection with the representative machine described. Its principal features consist in moving the box part in a generally horizontal or lateral direction to turn one or a plurality of adjacent cover margins to horizontal position, and then moving the box part in a generally vertical direction, or a direction of a right angle to the first movement and in the planes of the side walls, to turn one or a plurality of adjacent margins inward or parallel to the inner faces of the box walls, with subsequent pressure applied to affix the margins; and in some cases the process also includes the turning of the box part and repetition of the above described operations to turn and affix the remaining projecting margins.

I claim:

1. A method of turning and affixing cover margins employed in connection with box parts having cover margins projecting beyond the free edges of the side walls, comprising moving the box part in the plane of its bottom and during such movement turning a margin horizontally, then moving the box part substantially in the plane of a side wall and during such movement turning said margin inward against an adjacent inner face of a side wall, and then pressing the margin upon said wall.

2. Mechanism of the class described, comprising a movable box support, means for moving it, a fixed turning bar to turn a projecting cover horizontally by lateral movement of a box part on the support, the bar also serving to turn the margin inward when the support is moved to move the box part substantially in the plane of a side wall, and means then acting in co-operation with the bar to press and affix the margin.

3. Mechanism of the class described, comprising a frame, a fixed presser bar, a co-operating movable bar, a hydraulic actuator for the movable bar, a hydraulic driver connected to the actuator, a movable box support, and arbitrarily controlled means for moving the box support and for energizing the hydraulic driver in timed relation.

4. Mechanism of the class described, comprising relatively movable pressing bars, a

hydraulic actuator to move the bars convergently for pressing, a hydraulic driver connected to the actuator, means for positioning an article to be pressed in relation to the bars, 5 one of the cars being arranged to turn a box wall margin horizontally by a lateral movement of the box, and means for moving said positioning means vertically before the press-

ing operation to turn said margin down against an inner wall face by co-operation 10 with the pressing bar.

Signed at New York city, in the county of New York and State of New York this 22nd day of October A. D. 1925.

HARRY BRIDGMAN SMITH.
